UNITED STATES PATENT OFFICE.

LESLIE L. IRVIN, OF BUFFALO, NEW YORK, ASSIGNOR TO IRVIN AIR CHUTE CO., OF BUFFALO, NEW YORK, A CORPORATION OF NEW YORK.

METHOD AND APPARATUS FOR PROVIDING PARACHUTE SHROUD LINES.

Application filed May 15, 1925. Serial No. 30,564.

This invention relates to an improved method and apparatus for the production of parachute shroud lines.

The primary object of this invention is the provision of improved means and a novel method for accurately producing at the same time the entire number of shroud lines for a parachute, so that they will have similar characteristics as to length and elongation under tension.

It is extremely difficult to provide shroud lines of equal lengths which may be accurately attached to the chute or body of the parachute, and which shroud lines will hang "in the clear" for equal lengths. This is primarily so because of the huge size of parachutes, and because of the fact that usually it is impossible to place the shroud lines under the proper tension for cutting the same to the same lengths with the proper markings. It is therefore an object of this invention to provide the entire number of shroud lines for a single parachute at the same operation, quickly and with ease, with the proper markings thereon for accurate attachment at predetermined points on the chute portion and aviator's harness.

Heretofore it has been usual for an operator to measure the shroud lines into lengths and place the proper markings on the shroud lines where the same are to be attached or cut. This method is, however, not satisfactory because of the fact that when under tension the shroud lines may vary from the equality of lengths in which they were previously cut. It is therefore an important object of this invention to produce shroud lines for parachutes after a novel method, by which a predetermined quantity of lining material sufficient to produce the entire number of shroud lines for a single parachute is subjected to a tensioning at every point throughout its length, to render the same taut. In such taut position the shroud lines are then marked for cutting and attachment, and subsequently applied to the chute or aviator's harness as the case may be.

Other objects and advantages of this invention will be apparent during the course of the following detailed description.

In the accompanying drawings, forming a part of this specification, and wherein similar reference characters designate cor-

responding parts throughout the several views,

Figure 1 is a plan view of the improved apparatus, showing table or cord material placed upon the apparatus in proper relation to provide the entire number of shroud lines for a single parachute.

Figure 2 is an enlarged fragmentary plan view of the details illustrated in Figure 1, showing more particularly and specifically the relative arrangement of parts.

Figure 3 is a side elevation of the details illustrated in Figure 2.

Figure 4 is a view somewhat diagrammatically illustrating a single shroud line after the same has been cut, with the proper markings thereon showing attaching points by means of which the same may be applied to the body of the parachute or to the aviator's harness.

Figure 5 is an extended view of the shroud line illustrated in Figure 4.

Figure 6 is a sectional view taken through a type of roller about which the shroud lines are trained incident to their tensioning and production.

Figure 7 is an enlarged fragmentary view taken through a part of the apparatus, showing more particularly the means for attaching the ends of the shroud cord material upon the apparatus.

Figure 8 is a cross sectional view taken through a parachute, showing more particularly the arrangement which a single shroud line has in connection with the chute of the parachute and an aviator's harness.

In the drawings wherein for the purpose of illustration is shown only a preferred embodiment of the apparatus by means of which shroud lines are produced, the letter A may generally designate such apparatus, which may consist of a supporting table member B; roller means C fixed thereon; slideable roller means D provided thereon; and means E for moving the roller means D over the table B to render the line or cord material F taut prior to the marking of the same for the production of the shroud lines.

Each of the shroud members H is placed upon the parachute G so as to provide a lower portion 15 adapted for attachment to a buckle 16 or the like of the suspension strap; the side portion 17 "in the clear", which at its upper end is attached at 18 to

the lower edge of the parachute body 11. From this point the shroud member H continues upwardly along one side of the chute through a pocket radially across the chute body 11, providing a portion 19 which extends to the edge of the vent opening 12, where the same is stitched at 20. The shroud member H continues at a portion 21 diametrically across the vent opening 12, 10 and at the opposite side of the vent opening 12 from the attachment 20 said portion 21 is attached at 22, to the chute 11. The shroud member H then continues in a portion 25 radially across the parachute body 11, in diametrical alignment with the portion 19; this portion 25 at its lower end being stitched or otherwise affixed as at 27 to the lower edge of the chute body 11 diametrically opposed to the securing point 18.

20 The member H then extends downwardly "in the clear", at 30, and provides a lower portion 31 for attachment to the conventional D-buckle 32 of the aviator's harness suspension strap 13.

25 To facilitate attachment of each shroud member H to the chute and to the aviator's harness, it is thus necessary to place indicia, such as crayon marks at the junctures of the portions 15 and 17; 17 and 19; 19 and 21; 30 21 and 25; 25 and 30; and 30 and 31, in order to determine the points of connection for these portions with respect to the aviator's harness and the chute 11, as can readily be understood.

35 Referring to the apparatus A by means of which the marks are placed upon the shroud members H, and by means of which the shroud members H are each arranged under tension into equal lengths, the table B thereof is relatively narrow and of considerable 40 length, being formed of a board, or of any other preferred material. This table or support B is preferably plane, and is apertured, as will be subsequently mentioned, for the 45 reception of guide pins.

Referring to the roller means C, the same 50 comprises a series of anti-friction roller devices 35 placed in transverse alignment at one end 36 of the table or support B; preferably in alignment at right angles to the axis of the said support B. Each of these 55 anti-friction devices 35, preferably comprises a bolt or shaft member 38 fixedly extended through a passageway 39 in the support B; the screw threaded end 40 of the bolt 38 below the support B detachably receiving a nut and washer device 41, as is illustrated in Figure 6 of the drawings. At its upper end the bolt 38 is provided with a bolt head 42 and flanged washer 44; the washer 44 being held spaced by the bolt 38 above the top surface 45 of the support B; the bolt 38 rotatably receiving an anti-friction roller 47 below the washer flange 44, 60 which preferably rests upon a large washer

48 above the top surface 45 of the support B. The shank of the bolt 38 and preferably the roller 47 are held by the support B with the axis of the roller 47 at a slight acute angle with respect to a line normal to the top surface 45 of the support B. This has been illustrated in Figure 6 of the drawings, where the dot and dash line 50 refers to a line normal or at right angles to the support B and more particularly the top surface 45 thereof; and the line 51 refers to the axis of the roller 47. This arrangement has been provided in order to insure the retention of the shroud line material upon the rollers 47, 70 since the shroud line material is itself located in a plane at an acute angle with respect to the support B when the same is under tension for subdividing the same, as is illustrated in Figure 3 of the drawings.

75 The slideable roller arrangement D preferably comprises a bar 55 mounted on the table B for sliding therealong. This bar is relatively narrow and is disposed at right angles to the longitudinal axis of the board D. Adjacent the ends of the bar 55, cord holding members 56 are placed, which are of somewhat novel formation, each comprising a bolt 57 with its screw threaded end extending into the bar 55 and there being secured in any approved manner as by a countersunk nut 58. The head of the bolt 57 is kerfed, providing a slot 60 which extends parallel with the longitudinal axis of the table or support B, and is adapted to receive the shroud cord therethrough. These devices 56 are adapted to hold the ends of the shroud lining.

80 On the bar 55 between the cord attaching devices 56 are provided a plurality of roller devices 60 which are entirely similar to the structure of the roller devices 35, and which have not been specifically detailed in the drawings for that reason.

85 The means E for tensioning the cord prior to the severing thereof comprises a steel or wire cable 65 connected at one end to a drum or shaft 66; said drum or shaft 66 being rotatably journaled at 67 at an end of the table or support B opposite to the end 36; 90 said drum or shaft 66 having a crank 68 laterally of the table B to rotate the same whereby the cable 65 may be wound thereon or unwound therefrom. The cable 65 intermediate its ends may embody a scale or gauge 70 for determining the tension under 95 which the shroud cordage is placed. The cable 65 at its ends is provided with a pair of divergent portions 72, which connect to the extreme outer ends of the bar 55 of the roller structure D. The shaft 66 may have 100 a ratchet wheel 75 keyed thereto, against which a pawl 76 may operate to hold the drum or shaft 66 in a predetermined position, as is illustrated in Figure 3 of the drawings.

The shroud cordage is preferably supplied upon reels in quantity sufficient to supply all of the shroud lines for one parachute. This reel 80 is rotatably mounted upon the table B between the shaft or drum 66 and the movable shroud cord engaging device D.

As to the application of the cord upon the apparatus A, the operator starts the cord at one of the cord fastening devices 56, at an end of the bar 55 adjacent the reel 80, by tying a knot in the extreme end of the cord and slipping the cord through the slot 60 till the knot abuts the outer side of the bolt head 59, as is illustrated in Figure 7. The operator then runs the cord to the opposite end of the table to one of the anti-friction roller devices 35, trains the same around the roller 47 thereof, and returns the cord to the first roller 60 adjacent to that device 56 to which the cord has been fastened. The cord is then trained in parallel lengths back and forth in zig-zag relation between the roller projections of the fixed arrangement C and the movable arrangement D, until all of the rollers have been used, and the cord at its opposite end is then knotted and affixed to the other fastening device 56 in the manner above described. All of the cord from the reel is thus placed upon the apparatus A, and there are just twice as many parallel lengths of the cord extending between the devices C and D as there are shroud cords to be provided for one parachute. In other words, each shroud line includes two of the lengths positioned on the apparatus A prior to severing of the shroud lines from each other.

The cord having been unwound from the reel and placed as above mentioned the operator proceeds to rotate the crank 68 to wind the steel cable 65 upon the shaft or drum 66, and this pulls the bar 55 toward the shaft 66, and which will of course place the cord lengths under tension. The crank is rotated until the scale 70 registers the proper tension, and the pawl or detent 76 is then slipped against the teeth of the ratchet wheel 75 to hold the cords under this tension while the cords are being marked. Under this tension the operator marks the cords at the periphery of each of the rollers 60, of the slidable arrangement D, with a marking such as red crayon, and which marking designates the points of severance for the provision of the shroud lines of proper length. It can readily be understood that since each of the lengths of cord extending between the fixed and movable arrangements C and D respectively are under the same tension, the said marks placed upon the cord at the peripheries of the rollers 60 will subdivide the shroud lines into similar lengths under conditions which will insure that all of the shroud lines will be of the same length when

they are severed from each other upon these marks.

Pins 90 and 91 are detachably mounted in apertures provided in the table or board B, at opposite sides of the table or support B, and against these pins a guide bar or member 92 is adapted to be placed, providing a straight edge 93 extending at right angles to the run of the shroud lines over the table B. This guide bar 92 is of course disposed below the parallel lengths of cordage, and it is relatively simple for an operator to run a blue crayon or other marking device along the edge 93 to mark each length of cord material extending between the fixed and movable devices C and D respectively. When these marks have been placed the bar 92 is moved to another location for marking. The marks placed by the operator at the above mentioned location are at the juncture points between the portions 16 and 17 and the portions 31 and 30 of each shroud line H, and these marks have been designated at 95 in Figures 4 and 5 of the drawings.

After making the marks 95 the guide bar or member 92 is moved to a point closer to the roller arrangement C, where the pins 90 and 91 may be placed in apertures 96 and the bar 92 extended against said pins to place the straight edge 93 at right angles to the lengths of shroud material, and the operator may then draw his marking pencil or element across the shroud lines to place the markings which have been indicated by reference characters 97 in Figures 4 and 5 of the drawings, and which characters 97 designate the points of connection of the portions 17 and 19; and portions 25 and 30 of each shroud line H.

From its location against the pins in apertures 96 the guide bar 92 is next moved to a position immediately adjacent the roller devices 35, against the detachable pins 90 and 91 which may be placed in apertures 99, positioning the said guide rod or member 92 at right angles to the lengths of cord, and the operator then moves his pencil across the straight edge 93 for marking each length of line on the support B with marks 100, which determine the juncture points of the portion 21 with the portions 19 and 25 of each shroud line H.

The distance across the vent opening 12 of the parachute is practically the same in all cases, and the shroud line H from one mark 100 thereon to the other mark 100 thereon is practically 18 inches. Therefore, the openings 99 may be placed at a predetermined distance with respect to the transverse alignment of the roller arrangement C. However, as the diameters of the chutes 11 may vary from time to time, it can readily be understood that the marking points 97 may vary, and to this end other openings

102 are provided for detachably receiving the pins against which the guide member 92 engage. In similar manner the lengths 17 and 30, "in the clear" of each shroud line 5 H may vary, and for this adjustment other apertures 104 may be provided in the board B for detachably receiving the pins 90 and 91.

It should be mentioned that while training 10 the lengths of cord upon the rollers of the devices C and D, the movable bar 55 may rest against pins 110 provided upon the board B, to stably position the same to effect the winding operation. After the 15 cord has been placed upon the rollers in the proper position, the initial adjustment of the lengths of the cord may be effected by see-sawing the bar 55 back and forth flat upon the table.

20 After the cords have been marked as above described; it of course being understood that the marks at the peripheries of the rollers 60 are made with a different colored marking crayon or element than the marks 95, 97 25 and 100, the tension upon the lengths of cord is reduced, and the cord at the ends trained about the rollers 60, are slipped therefrom onto a suitable form, and dipped in wax for a short distance, and then the said cords are 30 severed on the marks which have been placed at the rollers 60. The wax or similar material is impregnated in the cords at these points of severance in order to prevent the fraying of the cords. The cords having 35 thus been cut provide shroud lines H of a number sufficient for one parachute, and these cords then appear as illustrated in Figures 4 and 5 of the drawings, and are ready for application to the chute 11, and 40 the suspension straps 10 and 13 of the aviator's harness.

By way of example the dimensions of the various portions of the shroud cord may be given. For instance, the lengths of the portions 15 and 31 up to the marks 95 preferably amounts to 6" in each case. The 45 lengths of the portions 17 and 30 "in the clear" are each about 15', for a conventional sized parachute. The cord lengths 19 and 50 25 which radially extend across the chute 11 to the vent opening 12 are each preferably about 11' 3", and the length of the vent portion 21 of each shroud cord amounts to approximately 18". These dimensions may 55 of course vary, as above indicated, and the illustration of these lengths in the views is merely diagrammatic, and may be departed from if desired.

From the foregoing description of this 60 invention it is apparent that a novel method and a novel apparatus for the production of shroud cords for parachutes has been provided, by which the length of the cords is determined while they are all under the same 65 tension. This cutting and production of

shroud lines may be quickly accomplished with but little cost of manufacture, and the shroud lines are accurately marked so that they may be quickly attached at the marked points to the particular places on the chute 70 and suspension straps of the harness. By such attachment a parachute is provided which is symmetrically formed without eccentric connections, so that the same will properly balance the aviator during a descent. After the cords have been severed and completed they may all be tied in skeins until used.

Various changes in the steps of the method, and changes in the shape, size, and arrangement of parts may be made to the apparatus of the invention without departing from the spirit of the same or the scope of the claims.

I claim:

1. That method of producing parachute shroud cords which consists in taking a continuous length of material, tensioning the same equally throughout its length, and subdividing the same into equal shroud line 80 lengths.

2. That method of producing parachute shroud lines which consists in taking a length of cord, tensioning the same equally throughout its length, indicating on said cord while under such tension places where the cord is to be severed, and subsequently severing the cord on said indications into predetermined lengths.

3. That method of producing a plurality 100 of shroud lines of equal length which consists in taking a length of cord, tensioning the same equally throughout its length, marking on the cord while under tension places where the cord is to be severed, and 105 subsequently severing the cord on said marks into a plurality of shroud lines of equal lengths.

4. That method of producing all of the shroud lines for a single parachute which 110 consists in taking a length of cord sufficient to furnish all of such shroud lines, stretching said cord taut from end to end, marking on said cord while taut a plurality of marks equally spaced with respect to each other, and subsequently severing said cord on said 115 marks into a predetermined number of equal lengths of shroud cords.

5. That method of producing shroud lines for parachutes which consists in placing a 120 length of cord under tension, marking the same while under tension into a plurality of equal subdivisions, placing contrasting marks at certain designated points in each of said subdivisions, and subsequently severing the 125 subdivisions upon said first mentioned marks only to provide a plurality of shroud cords of equal lengths.

6. That method of producing a plurality 130 of shroud lines for parachutes which consists

- in tensioning a length of cord, marking the same while under tension at predetermined equi-spaced points, marking the same while under tension with contrasting marks at 5 points on the cord between said equi-spaced points, and subsequently severing the cord at said equi-spaced points only into a plurality of lengths of shroud cords.
7. That method of producing a predetermined number of shroud lines from a continuous length of cord which consists in winding the cord into a plurality of adjacently disposed non-crossing and non-abutting lengths, placing the cord while disposed 10 in said lengths under an equal tension throughout the entire length of the cord, and severing the cord into the lengths as they are provided at the time of tensioning of the cord.
8. That method of producing shroud lines from a continuous length of cord which consists in training the cord zig-zag into a plurality of lengths of material between a series of fixed and a series of movable members, 15 moving the movable members to tension the lengths thus produced, and subdividing the material by cutting it at predetermined points.
9. That method of producing a plurality 20 of shroud lines from a continuous length of cord which consists in training the length of cord zig-zag alternately between a series of fixed and a series of movable members, fixing the ends of said cord, moving the movable members away from the fixed members to tension the cord, and subsequently at certain indicated points severing the cord.
10. That method of producing shroud lines for parachutes which consists in taking a continuous length of cord, training the same 25 zig-zag alternately between a series of fixed and a series of movable members, securing the ends of said cord, moving the movable members away from said fixed members to 30 tension the cord, marking the cord at predetermined points, and severing the cord on said marks to subdivide the same into a plurality of shroud lines of equal lengths.
11. That method of producing shroud lines for parachutes which consists in taking a continuous length of cord, training the cord alternately between two series of relatively 35 movable members to provide adjacent lengths of the cord, moving one series of members away from the other series of members to tension the cord lengths so wound about said members, and severing the cord lengths at certain indicated points with respect to said relatively movable members.
12. That method of producing shroud lines of equal lengths from a length of cord material which consists in training the cord material zig-zag alternately between two series of relatively movable members, securing the ends of said lengths of cord mate- 40 rial, moving one series of members away from the other to tension the lengths of said cord between one series of members and the other series of members, placing marks at predetermined points on said lengths of the material between said series of members, and subsequently severing the cord material on certain of said marks to subdivide the same into a plurality of shroud lines of equal lengths. 45
13. That method of providing shroud lines for parachutes which consists in providing a continuous length of cord material, training said cord material zig-zag from one series of members about another series of 50 members into a plurality of parallel lengths, relatively moving the series of members away from each other to tension the lengths of cord between one series of members and the other series of members, placing marks at the ends of the said lengths of cord at the members of one of said series, placing other marks on the lengths of cord between said series of members at predetermined distances with respect to said series of members, and subsequently severing the cord on the marks first made to subdivide the same into a plurality of shroud lines of equal lengths. 55
14. That method of producing shroud lines which consists in tensioning a shroud line equally throughout its length and while under tension placing marks at predetermined spaced points thereon where the same is to be attached to the body of the parachute. 60
15. That method of designating the attaching points of shroud lines which consists in placing a shroud line under equal tension throughout its length, and while so tensioned placing marks thereon at the points where the shroud line is to be attached to the parachute body and aviator's harness. 65
16. That method of producing shroud lines for a parachute which consists in arranging a continuous length of cord zig-zag into a plurality of parallel lengths of cord material, tensioning the same uniformly throughout their lengths, and while said cord is so tensioned designating thereon the severing points of said cord to provide a plurality of shroud lines. 70
17. That method of producing and tensioning shroud lines of parachutes which consists in taking a continuous length of cord, training the same zig-zag alternately between one series of members and another series of members, fixing the ends of said length of cord with respect to said series of members, moving the two series of members relatively apart to tension the lengths of cord material between said two series of members to a predetermined tension, marking said lengths of cord material at predetermined points while under tension, re- 75

leasing the tension, and severing the cord on certain of said marks into a plurality of equal length shroud lines.

18. In an apparatus of the class described the combination of a support, a pair of series of relatively movable members associated with said support, a flexible length of cord, means for fixing the ends of the length of

5 the cord with respect to said series of members with the said cord wound zig-zag and alternately from the one series of members about the other series of members thus subdividing the said cord into a plurality of 10 lengths of cord, and means for moving the 15 one series of members away from the other series of members to tension said lengths of cord.

19. In an apparatus of the class described the combination of a support, a pair of 20 series of relatively movable members carried by said support, a cord adapted to be wound zig-zag from the members of one series to the members of the other series to subdivide the cord into a plurality of lengths of 25 material, and means for moving the series apart thereby placing said lengths of cord between the same under tension.

20. In an apparatus of the class described the combination of a support, and a pair of 30 series of relatively movable members carried by said support, a cord adapted to be wound zig-zag from the members of one series to the members of the other series to subdivide the cord into a plurality of lengths of 35 material, means for moving the series apart thereby placing the lengths of cord between the same under tension, and means to facilitate marking the lengths of cord at predetermined points.

40 21. In an apparatus of the class described the combination of a support, a pair of series of relatively movable members carried by said support, a cord adapted to be wound zig-zag from the members of one series to the members of the other series to subdivide the cord into a plurality of lengths of 45 material, means for moving the series apart thereby placing the lengths of cord between the same under tension, and means to facilitate marking the lengths of cord at predetermined points between the pair of series of members.

22. In an apparatus for producing shroud lines the combination of a support, two series 55 of relatively movable members associated with said support, marking guide means associated with said support between said two series of members, and means for moving the series of members toward and away from each other.

23. In an apparatus of the class described the combination of a support, a plurality of 60 fixed projections carried as a series by said support, a plurality of projections carried as 65 a series and movable with respect to said

support, said projections of the fixed and movable series being adapted to receive a length of cord in zig-zag relation therebetween thus subdividing the length of cord into a plurality of lengths, and means for 70 moving said movable series of projections to place the lengths of cord under a predetermined tension.

24. In an apparatus of the class described the combination of a support, a plurality of 75 fixed projections carried as a series by said support, a plurality of projections carried as a series and movable with respect to said support, said projections of the fixed and movable series being adapted to receive a 80 length of cord in zig-zag relation therebetween thus subdividing the length of cord into a plurality of lengths, means for moving said movable series of projections to place the lengths of cord under a predetermined 85 tension, and guide means associated with the support between said fixed and movable series of projections to facilitate marking the lengths of cord at predetermined points.

25. In an apparatus for determining 90 lengths of cord an elongated support, a plurality of fixed cord receiving members arranged in a series transversely of said support, a bar movable on said support, a plurality of cord receiving members carried by 95 said bar, and means for moving the bar along the support.

26. In an apparatus for producing shroud lines an elongated support, a plurality of fixed members arranged in a series transversely of said support, a bar movable on said support, a plurality of members carried by said bar, means for moving the bar along the support, and a movable marker guide associated with said support between said 105 fixed and movable members.

27. In apparatus for producing and marking shroud lines for parachutes the combination of a support, a device on the support for movably receiving a length of cord intermediate its ends, a second device relatively movable on the support with respect to the first mentioned device for also receiving the length of cord thereover in slidable relation at a plurality of points on the second device, 110 means for relatively moving the devices towards or away from each other, and means for holding the ends of the cord so that as the devices are moved away from each other the cord will be rendered taut to provide a 115 plurality of cords of equal lengths extending between said devices.

28. In apparatus of the class described a support, means on the support for arranging a continuous length of cord taut thereover in 120 a plurality of parallel lengths of cord, pins carried by the support, and a guide bar associated with said pins for placement at right angles to the lengths of cord and beneath said lengths of cord whereby an oper- 125 130

ator may run a pencil along said bar for marking the lengths of cord accurately at predetermined distances thereon. 25

29. In apparatus of the class described 5 an elongated support, a series of rollers fixed at one end of said support, a bar transversely positioned on the support for movement longitudinally of the support, rollers carried by said bar, means at the ends of said bar 10 for fixing the ends of a length of cord to the bar with the cord wound alternately from the rollers fixed on the support to the rollers on said movable bar to subdivide the length of cord into a plurality of parallel lengths over said support, a shaft member rotatably carried by the support, a cable extending from the shaft to said bar adapted upon rotation of the shaft to wind on the same for moving the bar along the support 15 20 away from said rollers fixed with respect to said support, means for holding the shaft in a predetermined position to maintain the cord length tensioned, and means to guide the marking of said cord lengths at predetermined points along their lengths. 25
30. In apparatus for the provision of shroud cords for parachutes the combination of an elongated support, two series of relatively movable members mounted at opposite ends of said support, means for relatively moving said members towards or away from each other, a cord secured at its ends and wound zig-zag between said two series of members to provide a plurality of lengths of cord extending along said support, a straight edge transversely arranged across said support beneath said lengths of cord, and means for adjustably moving said straight edge to various positions along said support into predetermined relation with 35 said lengths of cord to facilitate marking thereof in predetermined spaced relation with said series of movable members. 40

LESLIE L. IRVIN.
